UNITED STATES PATENT OFFICE.

NEWTON K. BOWMAN, OF NORTH LAWRENCE, OHIO.

MANUALLY-OPERATED MINE-DOOR.

1,155,703.

Specification of Letters Patent.

Patented Oct. 5, 1915.

Application filed June 23, 1914. Serial No. 846,828.

To all whom it may concern:

Be it known that I, NEWTON K. BOWMAN, citizen of the United States, residing at North Lawrence, in the county of Stark and State of Ohio, have invented certain new and useful Improvements in Manually-Operated Mine-Doors, of which the following is a specification.

My invention relates to new and useful improvements in mine doors or barriers and has particular reference to an improved construction in doors of the type adapted especially for use in connection with manways.

The primary object of my invention is to provide a door which is equipped with sealing strips adapting the door for service as an effectual air barrier and is provided with an operating mechanism so constructed that putters or other pedestrians using the manway may open and close the door, either by hand or foot pressure.

A further object of my present invention is to fashion the sealing strips of canvas or some similar durable fabric and to so arrange them that the air current in the manway will constitute the force normally tending to hold the strips in sealing relation to the door and its frame.

A yet further object is to improve the general construction of the door so that it will embody the essential features of simplicity, durability and efficiency and may be readily and conveniently set up for operation with a minimum expenditure of time and labor.

The above and other incidental objects of a similar nature which will be hereinafter more specifically treated, are accomplished by such means as are illustrated in the accompanying drawings, described in the following specification and then more particularly pointed out in the claims which are appended hereto and form a part of this application.

With reference to the drawings, wherein there has been illustrated the preferred embodiment of this invention as it is reduced to practice, and throughout the several views of which similar reference numerals designate corresponding parts, Figure 1 is a perspective view showing the improved door in operative assembled relation to the mine car track, the major and minor doors being both shown in closed position; Fig. 2 is a horizontal section taken medially of the door and its frame. In this figure there is indicated, by dot and dash lines, a connect-

ing bar by which the major and minor sections of the door are so connected that the air pressure which would normally, due to the peculiar mounting of the door sections, tend to open the one and close the other, is so balanced that the doors are normally maintained in closed position; Fig. 3 is a detail perspective view of this connecting bar; Fig. 4 is a detail perspective view of the improved mounting which I employ in properly attaching the door operating lever to a cross sill; Fig. 5 is a section taken vertically through the minor door and the upper horizontal beam of the door frame or casing, illustrating, in detail, the manner in which the air sealing strip is arranged to normally prevent the passage of air through the door; Fig. 6 is a vertical section taken through the major door and upper horizontal beam of the door frame, illustrating particularly, the manner in which the sealing strip of the major door is so arranged that the current of air through the manway normally maintains the strip in sealing engagement against the major door.

Broadly, the door as illustrated in the embodiment shown in the accompanying drawings, includes as its essential features of construction a major and a minor door section, designated, respectively, by the letters A and B, a frame or casing C, in which the members A and B are hinged, and two independent door operating mechanisms which are designated, respectively, and as 90 entirieties by the letters D and E and are each adapted to move the two door sections A and B from open to closed position or closed to open position.

The major door section A is of rectangular shape and includes parallel side frame members 10 and 11, upper and lower horizontal frame members 12 and 13, respectively, and an intermediate horizontal frame member 14. These frame members of the door section may, of course, be constructed of metal or of wood and can be suitably joined by bolts, rivets or any other suitable fastening devices which may be found desirable. The spaces between the intermediate member 14 and the upper and lower horizontal frame members 12 and 13 are preferably occupied by sheet metal plates 15 and 16.

The minor door section B is, in construction, similar to the member A, including as it does, side frame members 17 and 18, upper

and lower horizontal members 19 and 20, an intermediate horizontal frame member 21 and the sheet metal plates 22 and 23. The frame members 11 and 17 of the major and minor door sections A and B may be equipped with sheet metal boxings 24.

The frame or casing C, in which the door sections A and B are hinged, in a manner to be hereinafter described, consists essentially in the uprights 25 and 26 and the upper and lower horizontal sills indicated at 27 and 28, respectively. The uprights are arranged on opposite sides of the rails 29 and 30 and the lower sill 28 is arranged beneath the rails. This lower sill serves not only as a portion of the frame in which the doors are mounted, but also takes the place of one of the cross ties. The sill 28, and consequently the entire door frame C, is arranged diagonally with respect to the track, the purpose in thus arranging the door frame being to so dispose the door sections A and B that they may be moved into open position by being merely swung through an arc of approximately 45 degrees, instead of an arc of 90 degrees as is usual in most door constructions. These two doors A and B are mounted for swinging movement in the casing C by hinges which are similar in construction and it is deemed necessary, therefore, to describe specifically the hinging elements of only one of the doors, the member A being chosen in this instance. From the lower terminal of the side frame member 10 of the major section A there depends a hinge rod 31 which is of such length that its lower reduced terminal may be inserted in the laterally extending apertured ear 32 which is formed on a hinge plate 33. This latter member is substantially U-shaped in conformation and braces the sill 28 so that it may be secured thereto by spikes or similar fastening means. The upper terminal of the member 10 carries a hinge rod 34 which is received within an apertured hinge plate 35. This member 35 is secured to the terminal of the upper horizontal beam 27 in a manner which will be more clearly apparent upon reference to Fig. 1.

It is now to be noted that the door sections A and B are of such width that their side frame members 11 and 17 overlap as disclosed particularly in Fig. 2 and that as indicated by the arrows in this figure, the two door sections are designed to swing in opposite directions when being either opened or closed. It is obvious that, by overlapping the free edge portions of the door sections, there is formed an effectual joint to prevent the passage of air between the doors. It will also be noted that, by mounting the door sections for swinging movement in opposite directions, each may be completely opened by being merely moved through an

arc of approximately 45 degrees. It will further be noted, however, that the pressure of the air current, assuming that it comes in the direction of the arrow marked "air line" in Fig. 1, would normally tend to open the major door section A and close the door section B. While it is, of course, true that the counterbalances carried by the door operating levers, to be hereinafter described, would normally overcome the air pressure and prevent the movement of the doors, it is obvious that were the air blast particularly strong, there would be a possibility of failure by the counterbalance and that, as a consequence, the door sections might be opened, with a resultant disaster through improper distribution of the ventilating air current through the mine. In order, therefore, to counterbalance the air pressure on the oppositely opening door sections A and B, these two members are freely connected by a bar of the type designated in Fig. 3 as an entirety by the numeral 36. This bar is made in two sections 37 and 38. Each section consists in two parallel spaced strips 39 and 40 which are maintained in any desired spaced relation by spacer blocks 41. Bolts, indicated at 42, are employed in properly securing the members 39 and 40 to these blocks.

In connecting the abutting members of the sections 37-38, I preferably employ a coupling consisting of two plates 43 and 44, each of which is equipped at both its upper and lower edges with a pair of parallel spaced inwardly extending flanges 45. The flanges are adapted to embrace the edges of the members 39 and 40 in the manner shown particularly in Fig. 3. When the plates 43 and 44 have been properly positioned against opposite edges of the two sections 37 and 38, clamping bolts, indicated at 46, are passed through the two plates and through the space between the strips of the sections 37 and 38. The outer terminals of the two sections 37 and 38 are pivotally connected as by pins 47 and 48 in Fig. 2 to the horizontally extending bracket arms 49 and 50, which latter members are suitably secured to the side frame members 10 and 18 of the major and minor sections A and B, respectively.

It will now be understood, upon reference to Fig. 2 particularly, that the movement of the major door section A into open position will, through the connecting bar 36, cause the opening of the minor door section B. It is equally apparent, however, that the current of air tending to open the member A is opposed by an equally forceful air current tending to move the door B to closed position (which is in a direction opposite to the opening movement of the section A). It will thus be observed that by means of the bar 36, I have so connected

the oppositely opening door sections A and B that the air current through the manway in itself constitutes the force necessary for normally holding the doors in closed position.

From the foregoing description of the connecting bar 36, it will be noted that the opening of either door section will cause the movement of the other door section into open position and that the same result will be accomplished when either door section is moved from open to closed position. It is of course desirable that it be possible to open the door sections when approaching either side of the door and for this reason, therefore, I have provided the two operating mechanisms which have been hereinbefore designated as entireties by the letters D and E. The members D and E are substantially identical in construction and it will be necessary therefore to describe only one of them in detail. Before taking up the detailed description of the member D, which has been chosen in this instance, however, it may be well to explain that the two mechanisms D and E are independent of one another so that the doors may be operated by either mechanism and that they are positioned on opposite sides of the track and opposite sides of the door sections.

The member D includes an operating lever which is pivotally mounted on one of the ties 51 and is operatively connected by a draw rod 52 to a fixed arcuate bracket arm 53, which as shown in Fig. 2 particularly, is secured to the door section B. The one terminal of the member 52 is, of course, connected by a pivot pin 54 to the bracket arm 53, while the other terminal is bifurcated and embraces the handle 55 of the operating lever, being pivotally connected thereto by a pin 56. The operating lever itself includes a socket 57 and an integral body plate 58, which extends laterally therefrom. A base plate 59 is secured to the tie 51 and pivotally supports the body plate 58. The body plate 58 is provided at each longitudinal edge with a plurality of laterally extending apertured ears 60 and carries at each terminal a depending apertured ear as indicated at 61 and 62. The base plate 59 is also equipped with ears 63 similar to the member 60 and with upstanding terminal apertured ears 64 and 65. It will be obvious, upon reference to Fig. 4 particularly, that the body plate 58 of the socket 57 may be quickly attached to the base plate 59 by passing the hinge rod 66 through the ears 61-62 and 64 and 65. Lateral and longitudinal strengthening ribs, indicated at 67 and 68 may be provided for the base plate 59, if found desirable. The lever handle 56, which is formed from a bar of metal, is properly secured by the insertion of its lower terminal in the socket 57. A bolt or similar fas-

tening device may be passed through an aperture 69 formed in the socket for holding the handle against accidental withdrawal. The handle is offset at its upper portion and is thereat provided with a series of spaced 70 apertures through which may be inserted an attaching pin 70 employed in adjustably securing a counterbalance weight 71 to the handle.

Interpolating briefly in regard to the 75 weight 71, it will of course be understood that this member, when beyond a dead center at either side of the hinge rod 66, will act as a gravity detent for preventing the movement of the doors into either open or 80 closed position, depending of course upon the disposition of the doors.

In order that the draw rod 52 may be manipulated by foot as well as by hand, it has been found desirable, in practice, to secure 85 to the body plate 58 a foot board 72. This member 72 may be held in any desired position by inserting bolts or similar fastening devices 73 through the board and ears 60 of the body plate.

It will now be apparent that either operating mechanism D or E may be manipulated manually or by foot pressure to either open or close the door according to the wishes of the operator. It will be further 95 apparent that when the door sections are in open position, the two weights of the members D and E will co-act to prevent the accidental return of the doors to closed position and that these weights will co-act in 100 the same manner when the door sections are in closed position to prevent their movement in closed position.

As has been hereinbefore explained, one of the important features of my invention is 105 the provision of means for sealing the space between the upper edges of the door sections and the upper horizontal frame member of the door casing. The means employed in this connection in the embodiment of the invention, illustrated in the accompanying drawings, includes a pair of sealing bars 74 and 75 and a pair of sealing strips 76 and 77. On the outer face of the upper horizontal frame member 27 of the door casing, as 110 shown in Fig. 1, I secure, by spikes 78, a strip 79. At one end of this strip 79, and to the lower face thereof, is attached the sealing bar 74 which is held in place by spikes 80 or equivalent fastening devices. 115 In Fig. 5, the minor door section B is illustrated in closed position and it will therein be seen that the sealing bar 74 is outwardly offset with respect to the door section B when this member is in closed position. The 120 sealing strip 76, which is preferably formed of heavy canvas, but may be made of any other material which is found desirable, extends entirely across the upper edge of the door section B and is so arranged that a 125

considerable free edge portion is located thereabove. It will be apparent, upon reference to Fig. 5, that the air current coming in the direction of the air line, indicated by an arrow, will, tend to urge the free edge portion of the sealing strip 76 against the sealing bar 74 with the result that the space between the upper edge of the door section B and the member 27 of the door casing will be sealed against the passage of air. The sealing bar 75, which is employed in connection with the major door section A, is secured by spikes 81 to the lower face of the frame member 27 and is arranged so that its forward edge overlaps the joint between the member 79 and the member 27. Thus, the sealing bar 75 is laterally offset with respect to the sealing bar 74 and is oppositely arranged with respect to the major door section A. It is necessary to arrange the sealing bar 75 so that it is offset interiorly from the side of the door exposed to the air current in order that the lower free edge portion of the sealing strip 77 may be urged against the upper edge of the member A by the air current. Nails or equivalent fastening devices may be employed in securing the members 77 to the sealing bar 75.

It is now to be noted as a matter of primary importance that the sealing bars and sealing strip are so arranged that even though the door sections, with which they are engageable, open in opposite directions, the air current through the manway will constitute the force necessary for normally holding the sealing strips in closed position with respect to the upper edges of the door sections.

In reduction to practice, it has been found that the form of this invention, illustrated in the drawings, and referred to in the above description as the preferred embodiment, is the most efficient and practical; yet realizing that the conditions concurrent with the adoption of this device will necessarily vary, it is desired to emphasize the fact that various minor changes in details of construction, proportion and arrangement of parts may be resorted to, when required, without sacrificing any of the advantages of this invention, as defined in the appended claims.

What is claimed as new, is:—

1. The combination with a mine door, including a pair of door sections arranged to open and close in opposite directions and disposed when in closed position to extend diagonally with respect to the track, means operably connecting the door sections whereby the movement of the one section is communicated to the other, and independent operating means connected to each of the sec-

tions, each means being operable for simultaneously opening or closing both door sections and including a fixed bracket secured to the door section, a door rod pivoted to the bracket at its one terminal and an operating lever pivoted to the door rod at its other terminal, said lever including a handle member whereby the door rod may be manually actuated, and a foot board adapted when depressed to operate the lever for moving the door sections into either open or closed positions.

2. A mine door of the character described including a pair of door sections, means operably connecting the door sections whereby the movement of one section will be communicated to the other section and operating means connected to one of the sections for moving both the sections into either open or closed position, said means including a draw rod pivotally connected to the rod sections and an operating lever pivotally connected to the draw rod, said operating lever including a socket, a body plate extending laterally thereof, terminally disposed depending ears formed on the body plate, a base plate, upstanding terminally disposed ears formed on the base plate, a hinged rod passing through the elongated base plate and of the body plate for pivotally connecting the said plates, a handle member removably seated in the socket, said handle member being manually operable and a foot board mounted on the body plate whereby the door sections may be moved into open or closed positions by foot pressure.

3. A mine door of the character described including a pair of door sections, means operably connecting the sections whereby the movement of the one will be communicated to the other, and an operating lever connected to one of the door sections, said lever including a socket, a body plate extending laterally therefrom, a handle removably received by the socket, said handle being manually operable, a base plate, depending ears formed on the body plate, upstanding ears formed on the base plate, a hinged rod passing through the body plate and base plate for hingedly connecting said plates, and a foot board rigidly mounted on the body plate, said foot board being depressible by foot pressure for either opening or closing the door sections.

In testimony whereof I affix my signature in presence of two witnesses.

NEWTON K. BOWMAN. [L.S.]
